Primary Examiner — Eric Goodman*Assistant Examiner* — Luqman McNeil(74) *Attorney, Agent, or Firm* — Maginot, Moore & Beck LLP(57) **CLAIM**

The ornamental design for a pressure washer, as shown and described.

DESCRIPTION

FIG. 1 is a perspective view of a pressure washer showing our new design;

FIG. 2 is a right side elevational view showing the design for the pressure washer of FIG. 1;

FIG. 3 is a front elevational view showing the design for the pressure washer of FIG. 1;

FIG. 4 is a left side elevational view showing the design for the pressure washer of FIG. 1;

FIG. 5 is a rear elevational view showing the design for the pressure washer of FIG. 1;

FIG. 6 is a top elevational view showing the design for the pressure washer of FIG. 1; and,

FIG. 7 is a bottom elevational view showing the design for the pressure washer of FIG. 1.

The broken lines shown in the drawings illustrate portions of the pressure washer that form no part of the claimed design.

1 Claim, 7 Drawing Sheets(56)
